MACHINE FOR APPLYING ADHESIVE TO
STRIP MATERIALSJoseph Ettl, Plainfield, N. J., assignor to Potdevin
Machine Company, Brooklyn, N. Y., a corpora-
tion of New York

Application April 30, 1937, Serial No. 139,907

26 Claims. (Cl. 91—50)

This invention relates to improvements in machines for handling strip material and is particularly directed to machines for applying adhesive material, such as glue, varnish and the like, to the face of paper strips or other material feed through the machine.

More specifically, the invention relates to machines of the character indicated wherein the material being applied to the strips is heated and the strips to which the material is applied are likewise heated as the same pass through the machine.

One of the objects of the present invention is the provision of a machine of the character indicated wherein heated fluid, such as oil, for example, is circulated in such a manner as properly to heat the strips as the same are passed through the machine to set the glue or varnish which has been applied thereto.

Another object of the invention resides in the provision of means for maintaining the strips heated until the same pass out of the machine to a chilling device where the glue or varnish is finally set.

Other objects of the present invention will be manifest from the following description and the accompanying drawings, in which

Fig. 1 is a side elevation of my improved device;

Fig. 2 is a plan view of the same with the upper roller and other parts removed for clarity of illustration;

Fig. 3 is a plan view of the machine; and

Fig. 4 is a sectional view of the heated blanket roller.

Referring to the drawings in detail: 2 designates a frame or support for the device having a pulley 4 mounted on a shaft 6 and driven from a suitable source (not shown) through a belt 8.

The shaft 6 carries a pinion 10 meshing with another pinion 12 which in turn is in mesh with a gear 14 on a shaft 16 carrying upper feed roller 18.

The gear 14 meshes with a gear 20 mounted on shaft 22 carrying a lower feed roller or blanket roller 24. This blanket roller is provided with a removable blanket 26, secured at one end to the roller by a clamp 28 which is pivoted at 30 and latched in clamping position by means of latch 32. The other end of the blanket is wound on a rod 34 having a pawl and ratchet arrangement 36 associated therewith for the purpose of tightening the blanket about the roller.

The blanket 26 receives adhesive such as glue or varnish from an adhesive-applying roller 38

mounted on a shaft 40 which is driven by means of a sprocket chain 42 from the shaft 6. The adhesive-applying roller 38 receives the adhesive from a roller 44 which dips into a tank 46 formed in the concaved cover of an enclosed heated oil tank 48 which will be described presently.

A table 50 is provided for feeding the strips of material to the machine. This table is supported at one end by the frame 2 of the machine and at its other end by a support 52. As the strips are fed from the table between the upper feed roller 18 and the blanket roller 24 the blanket 26 contacts the lower face of the strips and applies adhesive thereto. As the strips pass between the rollers the forward end thereof is gripped by a gripper 54 carried by the upper feed roller in the usual manner and conveyed about the feed roller 18 and deposited on a conveyor belt 56, which conveys the same out of the machine.

The blanket roller of the present invention is enclosed in a cylindrical housing 60, provided with a cover or door 62 hinged thereto at 64 to provide ready access to the blanket. This cover is provided with electric heating elements 66 receiving current from any suitable source of power through conductors 68. The cylindrical housing 60 also encloses a series of heating coils 70 through which heated oil or other fluid is circulated. The electric heating elements 66 and the heating coils 70, it will be appreciated, will maintain the blanket 26 in heated condition during the rotation of the roller.

The upper feed roller 18 is provided with a hinged cover or door 72 similar to the door 62 of the blanket roller 24 whereby inspection may readily be made.

As heretofore mentioned, one of the objects of the present invention resides in the provision of means for circulating heated fluid such as oil through the machine. The oil is heated in the closed tank 48 by means of an immersed electric heating element 76 which receives its energy from any suitable source through the conductors 75. A thermostatic switch may be provided in housing 77 for regulating or controlling the heat of the fluid in the tank 48.

A fluid conduit 78 leads from the bottom of the tank 48 to the intake side of a pump 80 driven by an electric motor 82.

Connected to the outlet side of the pump 80 is a conduit 84 provided with several branch lines. One of these lines leads to a drain 86 which when the valve 88 thereof is open will allow the tank 48 and all of the conduits herein-

after described to be drained of oil. Another branch line 90 leads to one end of the hollow shaft 40 of the adhesive-applying roller 38, the heating fluid passing out of this shaft at the other end through a coiled conduit 92 connected to one end of hollow shaft 94 of the roller 44, thence through the conduit 96 back to the tank 48. Another branch line leads from the pump 80 to the conduit 100, one branch 102 of which leads through the heating coils 70 in the blanket roller housing, thence through conduit 104 into the return line 106 and back to the tank 48. The other branch of the conduit 100 leads to the hollow shaft 22 of the blanket roller and as shown in Fig. 4 communicates with four branches 107, each leading to one of four chambers 108 in the blanket roller. The fluid passing into these chambers serves to heat the blanket roller from the interior and passes out of the chambers through branches 109 to return line 106 back to the tank 48. The tank 48 may be drained at 110 when the pump 80 is not in operation. The tank 48 is supplied with oil or other fluid from the filler tank 112 which has a conduit 113 in its lower end in communication with the return line 106 leading to the tank 48. The filler tank is also provided with an overflow line 114 communicating directly with the tank 48.

When the strips of material pass through the feed rollers and are deposited on the conveyor belt 56 they are subjected to further heat treatment. For this purpose I provide a heater 116 which is mounted on rails 118 directly above the conveyor belt 56. This heater receives its current through conductors 175 and may be controlled by thermostat 177.

The strips pass from the conveyor belt 56 to another conveyor belt 120, and as they are received by this last mentioned belt are subjected to a chilling action to finally set the adhesive which has been applied thereto. 122 designates the chilling unit which may be of any suitable type and which is mounted on a bracket 124 and hinged to the machine frame, the other end of the bracket 124 being supported on an adjustable bracket 126 whereby the chilling unit may be moved toward and away from the conveyor belt 120.

From the foregoing it will be appreciated that when the oil in the tank 48 is heated by means of the heating element 76 the heat will be transferred to the concaved cover containing the adhesive whereby the same will be maintained in a heated condition. The oil, as will be appreciated, is pumped from the tank through the various conduits described for the purpose of heating the blanket and the various rollers mentioned when the machine is in operation. The heating elements 66 in the cover of the blanket roller are electric heating elements. I prefer this arrangement rather than employing the heating pipes in the cover as a more convenient form. It will be appreciated, however, that the heating elements 66 will provide a continuity of heating surface for the blanket during its rotation.

It is to be noted that while I have illustrated and described a preferred embodiment of my invention, I do not wish to be limited to any specific form as various modifications and changes may be made therein without departing from the spirit and scope of my invention.

What I claim is:

1. A machine of the class described, comprising in combination a hollow blanket roller, coils

5 closely surrounding a major portion of the periphery of said roller, means for circulating heated fluid through said coils and through said roller to heat the interior and exterior of said roller.

2. A machine of the class described, comprising in combination a rotatable blanket roller, a cylindrical housing closely surrounding said roller, stationary coils adjacent said roller, electric heating elements adjacent said housing conduits in said roller, and means for circulating heated fluid through said coils and through said roller conduits to heat the interior and exterior of said roller, said electric heating elements complementing the said coils in heating the exterior of said roller.

3. A machine of the class described, comprising in combination a blanket roller, chambers therein, an enclosed fluid tank, means for heating 20 the fluid in said tank, coils adjacent said roller, conduits communicating with said tank coils and chambers, and a pump for circulating heated fluid from said tank to said chambers and coils and back to said tank to heat said roller interiorly and exteriorly.

4. A machine of the class described, comprising in combination a hollow blanket roller, a hollow adhesive-applying roller for applying adhesive to said blanket roller, an enclosed fluid 30 tank, a concaved cover for said tank containing adhesive, a hollow doctor roller in said adhesive for transferring adhesive to said adhesive-applying roller, means for heating said tank to heat the fluid therein and the adhesive, conduits leading from said tank to the interior of said hollow rollers, and means for circulating said fluid through said conduits to heat said rollers.

5. A machine of the class described, comprising in combination a blanket roller, chambers therein, an enclosed fluid tank, means for heating the fluid in said tank, a filler tank for maintaining said fluid tank filled, conduits communicating with said tank and chambers, and a pump 40 for circulating heated fluid from said tank through said chambers and back to said tank to heat said roller.

6. A machine of the class described, comprising in combination a blanket roller, a housing therefor, a movable cover for said housing, electric heating elements in said cover, fluid circulating coils in said housing, and means for circulating heated fluid through said coils, said electric heating elements and said coils heating 50 said blanket roller.

7. A machine of the class described, comprising in combination a blanket roller, a housing therefor, a hinged cover for said housing, electric heating elements in said cover, fluid circulating coils in said housing, a hollow adhesive-applying roller for applying adhesive to said blanket roller, and means for circulating heated fluid through said blanket roller, coils and adhesive-applying roller to heat the same.

8. A machine of the class described, comprising in combination a feed roller, a blanket roller, a housing for each of said rollers, a hinged cover for each of said housings, electric heating elements in the cover of the blanket roller housing, fluid circulating coils in said blanket roller housing, and means for circulating heated fluid through said coils, said electric heating elements and said coils heating said blanket roller and 70 strips of material fed through said rollers, the

78 housings serving to maintain heated air adjacent the rollers during the passage of the strips.

9. A machine of the class described, comprising in combination a blanket roller, a housing therefor, a hinged cover for said housing, electric heating elements in said cover, fluid circulating coils for said housing, a hollow adhesive-applying roller for applying adhesive to said blanket roller, an adhesive container, a fluid container, means for heating said containers, and means for circulating the heated fluid through said blanket roller, coils and the adhesive-applying roller to maintain the adhesive in heated condition during the application of the adhesive to strips of material fed through the machine.

10. In a machine of the class described, the combination of a feed roller, a blanket roller for feeding strips of material through the machine, housings for each of said rollers, a movable cover for each of said housings, heating elements in the cover of the blanket roller housing, heating coils in the blanket roller housing, an adhesive-applying roller for applying adhesive to said blanket roller, a conveyor belt for receiving the treated strips of material from said feed roller, an electric heating unit for heating the strips as the same are deposited on said conveyor belt.

11. A coating machine comprising a backing cylinder, a coating applying cylinder, a receptacle for coating material, a dipping roller dipping into said receptacle, a transfer roller fed by said dipping roller for transferring the coating material therefrom to said coating applying cylinder, heating means for said receptacle, dipping roller and transfer roller, said means being connected in series, means for circulating fluid through said heating means and an expansion element in the fluid circuit situated between said dipping roller and said transfer roller.

12. A coating machine comprising a backing cylinder, a coating applying cylinder, an oil supply, a receptacle for coating material having a jacket which forms a reservoir, a conduit connecting said reservoir to said oil supply, means for heating the oil in said reservoir, a hollow transfer roller, a hollow dipping roller dipping into said receptacle, automatic means to maintain the oil at a predetermined temperature, means to connect said dipping roller, and said transfer roller to said supply, means to cause the heated oil to circulate through said means, said rollers and said reservoir, and expansion means in said connecting means situated between said dipping roller and said transfer roller.

13. In a coating machine, a backing cylinder, a coating-applying cylinder, a receptacle for coating material, means for heating the coating material, a roller dipping into said receptacle, a transfer roller fed by said dipping roller for transferring the coating material therefrom to said coating-applying cylinder, means which partially enclose said coating-applying cylinder, heating means within and carried by said enclosing means, whereby the exterior of said cylinder may be heated to a predetermined temperature.

14. A coating machine comprising a coating roller, a housing therefor, a movable cover for said housing, means for rotating said roller in said housing, heating means within said covered housing in close proximity to the periphery of said roller, whereby the exterior of said roller is maintained at a predetermined temperature.

15. A coating machine comprising a coating cylinder, a coating-applying roller, for applying

78 adhesive to said coating roller, an enclosed fluid tank, a concave cover for said tank containing coating material, a dipping roller in said coating material for transferring the coating to said coating-applying roller, heating means in said tank to heat fluid therein, means for circulating said heated fluid to heat said rollers, and fluid conduits communicating with said tank and said rollers through which the heated fluid is circulated.

16. A coating machine comprising a coating roller, a housing therefor, a movable cover for said housing, electric heating elements in said cover, heating means in said housing, said electric heating elements and said heating means heating said coating roller.

17. A coating machine comprising a backing roller, a coating roller, a housing for each of said rollers, a hinged cover for each of said housings, electric heating elements in the cover of the coating roller, heating means in said coating roller housing, said electric heating elements and heating means heating said coating roller, and strips of material fed through said rollers, the housings serving to maintain heated air adjacent the rollers during the passage of the strips.

18. A coating machine comprising a backing roller, a coating roller, a housing for each of said rollers, a hinged cover for each of said housings, heating means in the cover and housing of the coating roller, said heating means heating said coating roller, and strips of material fed through said rollers, the housings serving to maintain heated air adjacent the rollers during the passage of the strips.

19. In a coating machine, comprising a backing cylinder, a coating-applying cylinder, a receptacle for coating material, means for heating the coating material, a roller dipping into said receptacle, a transfer roller fed by said dipping roller for transferring the coating material therefrom to said coating-applying cylinder, means which partially enclose said backing and coating-applying cylinders, heating means within and carried by the means which enclose the coating-applying cylinder, whereby the exterior of said cylinder may be heated to a predetermined temperature.

20. In a machine of the class described having a blanket cylinder and a backing cylinder contacting said blanket cylinder, a fountain, a fountain roller, a second roller fed by and in contact with said fountain roller and said blanket cylinder, heating means for said fountain, fountain roller and second roller, said means being connected in series, means for circulating fluid through said heating means, and expansion elements in the fluid circuit allowing relative movement between the said rollers.

21. In a machine of the class described having a heated fountain for coating material, a heated fountain roller dipping into said fountain, a backing cylinder, a blanket cylinder contacting said backing cylinder, and a heated hollow transfer roller adapted to contact the blanket cylinder and the fountain roller, a supply of heating fluid, a fluid conduit leading from said supply to said heated fountain where the fluid is heated, a fluid conduit connected to said fountain and rollers for supplying heated fluid thereto, and expansion coils in said conduit to allow said rollers to move relatively to each other.

22. A machine of the class described comprising in combination a hollow blanket roller, a hollow adhesive applying roller, a cylindrical hous-

ing closely surrounding said blanket roller, a supply of heated fluid, coils adjacent said blanket roller and within said housing, and means for circulating said heated fluid through said rollers to heat the same and through said coils to heat the surface of said blanket roller.

23. A machine of the class described, comprising in combination a blanket roller, a cylindrical housing closely surrounding said roller, fluid conduits in said housing, a supply of heated fluid, fluid chambers in said roller about the periphery thereof, conduits leading from said supply of heated fluid to said fluid chambers and out of said chambers back to the said supply, and means for circulating said heated fluid through said conduits and chambers to heat said roller.

24. A machine of the class described, comprising in combination a blanket roller, a housing therefor, fluid conduits in said housing in close proximity to the periphery of said roller, a plurality of communicating fluid chambers within and adjacent the peripheral wall of said roller, a fluid tank, means for heating the fluid therein, conduits leading from said tank to said fluid chambers and back to said tank, a pump for circulating heated fluid from said tank through said conduits and chambers to heat the interior and exterior of said roller.

25. In a device of the class described the combination of an oil supply, a blanket cylinder, a fountain for coating material, a hollow fountain

roller dipping into said fountain, said fountain having a jacket which forms a reservoir, a conduit connecting said reservoir to said oil supply, a hollow transfer roller contacting said blanket roller and fountain roller, a conduit connecting said transfer and fountain roller and providing a flexible connection therebetween, automatic means to maintain the oil at a predetermined temperature, means to retain heat in the vicinity of said blanket roller, and means to cause said oil to circulate through said jacket and the hollow transfer roller.

26. In a device of the class described the combination of an oil supply, a blanket cylinder, a backing cylinder contacting said blanket cylinder, a hollow transfer roller contacting said blanket cylinder, a fountain for coating material, a hollow fountain roller dipping into said fountain and contacting said transfer roller, a jacket for said fountain which forms an oil reservoir, a conduit connecting said reservoir with said oil supply, means for heating the oil in said reservoir, automatic means for maintaining the oil at a predetermined temperature, a conduit providing a path for heated oil from said reservoir to the interior of the fountain roller and transfer roller and providing a flexible connection between said rollers, means to cause heated oil to circulate through said conduits, hollow rollers and reservoir.

JOSEPH ETTL.
